[57] CLAIM

The ornamental design for an element for a manure container, substantially as shown.

DESCRIPTION

FIG. 1 is a front perspective view, viewed from the front and one vertical edge, of an element for a manure container embodying my new design, the bottom of the element or module in the normal erected position thereof being the right hand edge portion of FIG. 1; FIG. 2 is a perspective view viewed from the rear and the opposite edge of the element relative to that shown in FIG. 1; and

FIG. 3 is an end elevational view of the element, the opposite end elevation being the mirror image thereof.
